UNITED STATES PATENT OFFICE.

ALBERT T. MAHR, OF BINGHAMTON, AND CHARLES MILLER, OF OLEAN, NEW YORK.

SANITARY BEER-COOLER.

1,127,057.

Specification of Letters Patent.

Patented Feb. 2, 1915.

Application filed December 26, 1913. Serial No. 808,690.

To all whom it may concern:

Be it known that we, ALBERT T. MAHR and CHARLES MILLER, citizens of the United States, residing, ALBERT T. MAHR at Binghamton, in the county of Broome and State of New York, and CHARLES MILLER at Olean, in the county of Cattaraugus and State of New York, have invented certain new and useful Improvements in Sanitary Beer-Coolers, of which the following is a specification.

Our invention relates to an improvement in sanitary beer coolers, in which beer or other liquor, as it passes from the kegs to the outlet for trade use, is cooled quickly and in a sanitary manner, and it has for its object to provide a means for readily cooling liquor and at the same time readily and quickly cool the different parts of the cooling receptacle, and to provide a means whereby the interior of the cooling receptacle can be easily reached for cleansing and washing to remove all unsanitary elements, for it is to be noted that when beer or other liquor stands in a cooling receptacle or passes through those usually provided it leaves a sediment which renders the receptacle soon impure and unsanitary, and which has a deteriorating effect upon the liquor.

With these objects in view our invention consists in certain novel features of construction and arrangement of parts as will be hereinafter fully described and pointed out in the claims, reference being had to the accompanying drawings, in which—

Figure 1 is a view of one of our devices in an ice box with a view shown of the box in cross section. Fig. 2 is a front view of a set of four of our devices in an ice box with a view of the ice box taken in cross section.

The same reference characters denote like parts in each of the several figures of the drawing.

In carrying out our invention we provide the parallel tubes A, B. Tube A has mounted within it at the bottom the screw cap C, and from which projects the handle support 2, and tube B has mounted within it at the bottom the screw cap D from which projects the handle or head 2. Between tubes A and B there extends the connecting tube E similar in size to tubes A and B. Mounted in the top of tube B is the screw cap F. Mounted on screw cap F we have the union G, and mounted in union G we

have the intake pipe H. Tube A has the curved neck I, to which is attached the union J, into which is let or attached the outlet pipe or faucet K. It will be noted that for the purpose of holding the flow of the beer or liquor in the container received through the intake pipe H, that tube B is flattened so as to produce the flattened surface or portion L, while tube A is reduced in size as it approaches to the neck I.

In the operation of our device we unite within an ice box M, a set of four or more of our devices, as shown in Fig. 1. We surround the same with ice packed in the usual manner between the two. We open the intake pipe H, and the beer or other liquor flowing in passes through cap F and into tube B and against the flattened surface L, then through connecting tube E into tube A and out through neck I and through the union J and pipe or faucet K.

When we desire to cleanse the device, having shut off the inflow, we disconnect the intake pipe H and remove the tubes. Then removing cap F and cap D of tube B, and cap C of tube A, the interior of the tubes can be readily cleansed by means of brushes or other means and all particles of impurities removed. Having thus cleansed the tubes we again remount the caps, form the connection with the union, place the devices in the ice box and when the ice is applied the device is ready for use.

Having thus described our invention, what we claim as new and for which we desire Letters Patent is as follows:

1. In a beer cooler, an ice receptacle, a series of double tubes mounted within the same, each series consisting of two vertical parallel tubes, a connecting tube between each set of parallel tubes, the one tube, an intake tube, the other tube the outlet tube, a screw cap closing the lower end of each tube, a screw cap mounted on the upper end of each intake tube and a coupling carried by each of said last mentioned caps, the outlet tube being of greatly reduced diameter at its upper end, the intake tube having two flattened opposite side surfaces and connecting means between the intake tube and the supply.

2. A beer cooler, comprising an inlet tube, and an outlet tube communicating with each other near their lower ends, the two tubes being substantially parallel with each other and spaced apart to permit ice to be packed

- between them, the outlet tube greatly decreasing in diameter toward its upper or discharge end, the inlet tube being provided with two opposing flat and broadened side walls, a supply pipe communicating with the inlet tube and an ice receptacle surrounding both the inlet and outlet tubes.
3. In a beer cooler, an inlet tube, and an outlet tube communicating with each other near their lower ends, the inlet tube being provided with opposing flat walls, which converge toward each other and provide a

restricted passage within the inlet tube, the outlet tube greatly decreasing in diameter toward its discharge end, and an ice receptacle surrounding the tubes. 15

In testimony whereof we have affixed our signatures in presence of two witnesses.

ALBERT T. MAHR.
CHARLES MILLER.
